UNITED STATES PATENT OFFICE.

MOSES M. LAHUE, OF LOWELL, MASSACHUSETTS.

LUG-STRAP SUPPORTER FOR LOOMS.

1,250,327.

Specification of Letters Patent. Patented Dec. 18, 1917.

Application filed October 7, 1916, Serial No. 124,273.

To all whom it may concern:

Be it known that I, MOSES M. LAHUE, a citizen of the United States, residing at Lowell, in the county of Middlesex and 5 Commonwealth of Massachusetts, have invented a certain new and useful Improvement in Lug-Strap Supporters for Looms, of which the following is a specification.

This invention relates to lug-strap supporters for looms, and consists in the devices and the combinations hereinafter described and claimed.

The general object of this invention is to support the outer end of the lug strap or 15 sweep strap at the desired height on the picker-stick and thereby to regulate the length and force of the stroke of said stick.

The supporter herein described and designed to provide a double cushion for the 20 picker-stick and thereby lessen the shock between said stick and the lug-strap when the picker is thrown outward by the incoming shuttle and also when the said stick is suddenly thrown inward by the pull of 25 said strap, and thus to prevent breaking of the filling and lessen the wear and damage to pickers, picker-sticks, shuttles and other parts of the loom.

In carrying out my invention, I use a 30 housing of rigid material, preferably metallic, as malleable iron, adapted to support an inner cushion next the picker-stick and an outer cushion between the body of the housing and the closed end of the loop which 35 forms the outer member of the lug strap, and between the outer cushion and said closed end of said loop I interpose a wearing piece or gib of suitable material as indurated fiber.

40 The housing is adapted to support the cushions near their ends in such a manner as to allow them to approach each other in their middle portion when tension is put on the lug-strap either by the outward 45 movement of the picker-stick or by the pull of the picking tappet.

These cushions or shock-absorbers will 50 preferably be made of old or discarded double leather belting such as may be found in textile factories and which otherwise may be regarded as waste, and in shape are represented as an oblong double washer or washer with two holes one for each side of the loop.

55 In the accompanying drawing Figure 1 is

a front elevation of certain parts of a loom showing the picking mechanism provided with my invention; Fig. 2, a front elevation of parts of the picker-stick and lug-strap and the improved lug-strap holder; Fig. 3, 60 a section on the line 3 3 in Fig. 2; Fig. 4, an elevation of the outer end of the housing detached and without the cushions and gib; Fig. 5, a section on the line 5 5 in Fig. 3, omitting the picker-stick, except that the 65 gib is in elevation; Fig. 6, a side elevation of a cushion, the full lines showing the outline of the outer cushion and the dotted lines showing the variation of the outline of the inner cushion from that of the outer. 70

The following named parts of a loom are in common use and may be of any usual construction:

1, indicates a loom side; 2, a portion of the breast beam; 3, the lay beam and shuttle-box; 4, a picker-stick; 5, its rocker; 6, the rocker stands or outer end of the rock shaft of the lay; 7, the strap which connects the lower end of the picker stick to the rocker-spring 8; 9, the cam-shaft; 10, the 80 picking tappet on said shaft; 11, the picking cone carried by the arm 12 of the picking-shaft, 13; 14, the picking arm engaging the loop 15 which forms the inner member 85 of the lug-strap; 16, the wire loop or outer member of the lug-strap. It will be understood that the closed end of the loop 16 surrounds the picker-stick in the usual manner.

A denotes the housing of the lug-strap holder; a, the body thereof provided with holes a^1 a^1 through which the sides or limbs of the loop 16 pass; a^2 , a^2 , the curved guards which prevent lateral or longitudinal movement of the shock absorbing cushions B B¹. The body of the housing is alike 95 on both the outer and inner faces except as hereinafter stated and is provided with recesses a^3 a^3 midway between the holes a^1 a^1 at right angles to a line joining the center of said holes, these recesses being to facilitate the yielding of the middle portions of the cushions under pressure, upon the outer cushion B by the gib C and upon the inner cushion B¹ by the picker-stick, said gib and picker-stick being in alinement with 100 said recesses. The upper side of the housing is provided with an eye a^4 to receive a flexible strap D, as of leather, by which the housing is supported on the picker-stick, as shown in Figs. 1 and 2, said strap D being 110

looped through said eye and secured to said stick, as by a bolt d which passes into or through said stick.

The housing A has two guides E E¹ which project from the outer face of the body of said housing and are arranged parallel with each other and are provided with parallel wings e e to receive the ends of the gib C, and in alignment with the recesses a³ a³ and the free ends of these guides project beyond the outer ends of the wings e e far enough to be turned down over the ends of said gib as shown in Figs. 1 and 2, to retain said gib in position against the outer face of the outer cushion B. In Figs. 4 and 5 the guides are shown as they appear before being turned down on the gib.

The housing A with its guards, a² a², eye a⁴ and guides E E¹ is cast in one piece, preferably of malleable iron.

The cushions B B¹ are preferably made of old double belting which has a slight but sufficient elasticity to absorb the shocks caused by the impact of the shuttle and violent pull of the lug strap on the picker-stick.

The cushions B B¹ may be precisely alike and of the shape shown in full lines in Fig. 6 and formed by a single die, but the notches b² b² in the outer cushion B serve only to receive the wings e e and are therefore not needed in the inner cushion B¹ and the straight portions b⁴ b⁴ between these notches fit the guides E E¹ between said wings, but as these guides and wings are used only on the outer face of the housing, the upper and lower edges of the inner cushion may be continuous curves, as indicated partly by dotted lines b³ b³ in said Fig. 6.

40 The supporter is suspended as shown with its inner cushion against the picker stick and its outer cushion against the gib, the outer lug-strap member passing through the holes b b¹ in the cushions and body of the housing.

I claim as my invention:

1. A lug-strap supporter for looms comprising a metallic body, provided with means for holding cushions on opposite faces thereof, said cushions, guides, a gib,

arranged in said guides and adapted to receive the stroke of the outer loop member of the lug-strap, said body and cushions having holes to receive the sides of said loop member.

55

2. A lug-strap supporter for looms comprising a metallic body, provided with means for holding cushions on opposite faces thereof, said cushions, guides, a gib, arranged in said guides and adapted to receive the stroke of the outer loop member of the lug-strap, said body and cushions having holes to receive the sides of said loop member and said body having recesses to receive the yielding parts of said cushions.

60

3. A lug-strap supporter for looms comprising a metallic body, provided with an eye to receive a supporting strap adapted to be secured to the picker-stick of a loom and also provided with means for holding cushions on opposite faces thereof, said cushions, guides, a gib, arranged in said guides and adapted to receive the stroke of the outer loop member of the lug-strap, said body and cushions having holes to receive the sides of said loop member and said body having recesses to receive the yielding parts of said cushions.

75

4. A lug-strap supporter for looms comprising a metallic body, provided with guards to prevent lateral and longitudinal displacement of cushions, said cushions, a gib arranged to receive the stroke of the outer loop member of the lug-strap, said body and cushions having holes to receive the side of said loop member.

80

5. A lug-strap supporter for looms comprising a metallic body, cushions arranged on opposite faces of said body, a gib of indurated fiber arranged in contact with the outer one of said cushions, and guides for said gib in combination with a lug strap adapted to bind said metallic body, cushions and gib together.

90

In testimony whereof, I affix my signature hereto in presence of two witnesses.

MOSES M. LAHUE.
